UNITED STATES PATENT OFFICE.

PETER SCHROEDER, OF TWO RIVERS, WISCONSIN.

SAFETY LAMP-BURNER.

1,083,220.

Specification of Letters Patent.

Patented Dec. 30, 1913.

Application filed May 10, 1913. Serial No. 766,771.

To all whom it may concern:

Be it known that I, PETER SCHROEDER, a citizen of the United States, residing at Two Rivers, in the county of Manitowoc and State of Wisconsin, have invented new and useful Improvements in Safety Lamp-Burners, of which the following is a specification.

The invention relates to lamp burners and combines therewith unique means for extinguishing the light in the event of the lamp overturning or falling to the floor, thereby preventing a conflagration.

The invention consists of opposed light extinguishing members arranged upon opposite sides of the wick tube and connected in such a manner as to move simultaneously in opposite directions, inclined planes at the sides of the wick tube and ball weights arranged to move upon the inclined planes to cause the extinguishing members to close over the wick tube and extinguish the light should the lamp overturn or fall upon the floor.

The invention further consists of the peculiar construction and arrangement of the inclined planes and the supporting means therefor, whereby the ball weights are caused to positively operate to close the extinguishing members over the wick tube in an emergency such as the overturning or falling of the lamp.

The invention consists of the novel features, details of construction and combination of parts, which hereinafter will be more particularly set forth, illustrated in the accompanying drawing, and pointed out in the appended claims.

Referring to the drawing, forming a part of the specification, Figure 1 is a vertical central section of a lamp burner provided with automatic light extinguishing means embodying the invention. Fig. 2 is a view similar to Fig. 1, showing the operation of the invention. Fig. 3 is a detail perspective view of the body portion of the burner, the gallery and hood being removed. Fig. 4 is a side view of the burner. Fig. 5 is a detail perspective view of the inclined planes and supporting brackets.

Corresponding and like parts are referred to in the following description, and indicated in all the views of the drawing, by the same reference characters.

The invention is designed chiefly for

burners for coal oil lamps and is shown in this connection in the accompanying drawing, the burner being of ordinary construction and comprising a body 1, wick tube 2, gallery 3 and hood or guard 4. A band 5 is slipped upon the wick tube 2 and has the extinguishing members 6 pivoted thereto, said members being of like formation and pivotally connected at each end, as shown at 7, to cause both members to move uniformly. Each of the extinguishing members is made hollow upon its inner side so that when the two members come together they extend over and completely inclose the upper portion of the wick tube and wick, thereby extinguishing the light in an emergency. The band 5 is provided at its ends with extensions to which the arms of the extinguishing members 6 are pivotally connected at 8. The pivot connections 8 consist of short lengths of wire which extend along opposite sides of the wick tube and pass through openings formed in the arms of the parts 6 and extensions of the band 5, the projecting ends of such wires being bent. The band 5 fits the wick tube closely and is retained in place thereon by frictional engagement, hence the band with the attached extinguishing members may be readily removed or placed in position when required.

Two planes 9 are located at the sides of the wick tube and incline in opposite directions and curve slightly throughout their length, the curvature being gradual from a middle point toward opposite ends, the purpose being to centralize the ball weights 10 which are loosely mounted upon the planes 9 and are retained in place by the hood or guard 4. The planes 9 are formed of foraminous or reticulated metal to admit of an unobstructed passage of the air. The inner edges of the planes are spaced from the wick tube so as to give ample clearance for the extinguishing members 6, which normally occupy a position so as not to interfere with the light. The outer lower edges of the planes 9 rest upon the base of the burner body, whereas their end portions are attached to arms 11 of U shaped standards 12, which latter are secured at their lower ends to the base of the lamp body. The standards 12 with their arms 11 constitute bracket supports for the inclined planes 9. The arms 11 incline in opposite directions in

conformity to the outward and downward inclination of the planes 9. The planes 9 are secured to the arms 11 in any way and are also made fast at their outer lower edges 5 to the base of the body 1.

The ball weights 10 rest loosely upon the planes 9 and are retained in place by the hood or guard 4. In the event of the lamp tipping or falling upon the floor one or both 10 weights will roll upon the inclined planes and come in contact with one or both of the extinguishing members 6 and press the same inward, with the result that both members by reason of their mounting and connection 15 will close over the end of the wick tube and wick and extinguish the light.

It will be observed that the invention is of such a nature as to be readily applied to any type or design of lamp burner in use 20 or constructed.

The several pivot fastenings 7 and 8 between the extinguishing members and the band 5 are such as to admit of a limited play whereby the members 6 may open and close.

25 The pivot fastening 7 between the extinguishing members causes both to move together so that when one of the ball weights only comes in contact with an extinguishing member both extinguishing members move in unison and close over the wick so as to effectually extinguish the flame and prevent fire.

Having thus described the invention what is claimed as new, is:—

1. In a burner embodying a wick tube, extinguishing members pivotally supported upon opposite sides of the wick tube and pivotally connected to move together, inclined planes located at the sides of the wick tube, and ball weights arranged upon the inclined planes to move thereon and come in contact with an extinguishing member to effect a closing of both of such members over the wick to automatically extinguish the light in an emergency. 35 40 45

2. In a lamp burner embodying a wick tube the combination of a band mounted upon the wick tube, extinguishing members arranged upon opposite sides of the wick tube and adapted to close thereover, means pivotally connecting the extinguishing members to the band, other means pivotally connecting the extinguishing members to cause them to move together, inclined planes at the sides of the wick tube, and ball weights supported upon the inclined planes and adapted to effect automatic closing of the extinguishing members. 50 55

In testimony whereof I affix my signature in presence of two witnesses.

PETER SCHROEDER.
